UNITED STATES PATENT OFFICE.

GRAHAM H. JACKSON, OF NEWARK, NEW JERSEY, ASSIGNOR TO UNIVERSAL TOBACCO MACHINE CO., OF NEW YORK, N. Y., A CORPORATION OF NEW YORK.

TOBACCO-MACHINE.

1,366,386.

Specification of Letters Patent. Patented Jan. 25, 1921.

Application filed January 8, 1918. Serial No. 210,818.

To all whom it may concern:

Be it known that I, GRAHAM H. JACKSON, a citizen of the United States, and a resident of Newark, county of Essex, State of New Jersey, have invented certain new and useful Improvements in Tobacco-Machines, of which the following is a specification.

My invention relates to tobacco machines and has for its object to provide an improved stripping mechanism whereby the stripping of the leaf is accomplished in a novel and efficient manner and so as to reduce the waste in both stem and leaf to a minimum. Other objects of my invention will appear in the description hereinafter and the features of novelty will be pointed out in the appended claims.

Reference is to be had to the accompanying drawings in which I have shown my improvements incorporated in a combined stripping and booking machine of the type shown in the Deiller and Deiller Patent No. 985,984 of March 7, 1911. It is to be understood that this is only an example used for illustrative and descriptive purposes and that my invention is equally well adapted for combination with other machines which either strip and book the leaf or which simply strip the same. In said drawings Figure 1 is a side elevation of a tobacco machine including my improvements; Fig. 2 is a vertical section thereof; Fig. 3 is a detail plan view; Fig. 4 is a face view of one of the cutting members; Fig. 5 is an edge view showing a pair of cutting members in operative relation to each other; Fig. 6 is a view similar to Fig. 2 but illustrating a different form of cutting member; Fig. 7 is a face view of said cutting member; Fig. 8 is a detail section showing a different form of cutting arrangement; Fig. 9 is a detail plan view thereof and Fig. 10 is a face view of a tobacco leaf after it has been stripped according to my improvements.

The general construction of the tobacco stripping and booking machine which has been chosen herein as a medium for illustrating an example of my improvements is clearly described in the patent hereinbefore referred to, and with the exception of the changes and additions hereinafter referred to may remain the same in the present case. The machine in question comprises an upright frame 15 of suitable construction, upon which a transverse shaft 16 is journaled in

suitable bearings 17. This shaft 16 carries two sections 18 and 19 which together form a booking drum upon which the tobacco leaves are booked, after being stripped; each drum section 18 and 19, in the present case, is provided with a hub 20 and a set screw 21 whereby said sections are secured upon the shaft so as to be adjustable lengthwise thereof for the purpose to be more fully explained hereinafter. The illustrated machine also includes the endless belts 22 which pass over the drum sections 18 and 19 and over rollers 23, 24, 25, 26 and 27 journaled in suitable bearings upon the frame 15 and whereby the booked leaves are maintained upon the booking drum in the well known way; the belts are maintained under the proper tension at all times by tension rollers 28 carried by pivotally mounted bell cranks 29 controlled by counter-weights 30. The driving mechanism whereby the machine is operatively driven may comprise any suitable arrangement and in the present case consists of a main shaft 31 journaled on the frame 15 and carrying a pinion 32 in mesh with a gear 33 also rotatably mounted on said frame 15. The gear 33 in turn is in mesh with a pinion 34 operatively combined with the roller 23 for instance by being mounted upon the same shaft. The driving mechanism may further include a pulley 35 loosely mounted on the shaft 31 and driven by means of suitable belt and power mechanism; the pulley 35 may form one member of a clutch, the other elements 36 of which are secured upon the shaft 31 to rotate therewith the clutch mechanism may be thrown into and out of operation by a suitable lever 37 pivotally mounted at 38 upon the frame 15 and operatively connected by means of a link 39 with a suitable foot treadle 40. The details of construction and method of operation of the clutch mechanism so far described and whereby the machine is manually controlled may be the same as in the patent hereinbefore referred to. The preferred arrangement further includes means whereby the clutch mechanism is operated to automatically stop the machine at given intervals; this means will be more fully referred to and described further on in the description. With the arrangement set forth power is applied to the main shaft 31 and pinion 32 each time the treadle 40 is operated to throw in the clutch elements 36

whereby the pulley 35 and shaft 31 are operatively connected and is transmitted through the medium of the gear 33 to the pinion 34 and roller 23; in this manner the belts 22 5 are driven and in turn serve to rotatably drive the transverse shaft 16 and booking drum sections 18 and 19. The machine so far described may further include a hand lever 41 and links 42 for operating the apron 10 43 in a manner to provide free access for instance to the completed books of tobacco leaves when it is desired to remove same. In addition to the above any other elements and features customarily found in machines 15 of the type in question may be included, the details of construction and operation of the illustrated machine, excepting in so far as they relate to my improvements and have been changed, added or provided by me, not 20 being essential to my invention.

My improvements relate essentially to the stripping mechanism and in the illustrated example comprise cutting members 44 and 45 in the nature of circular knives which in 25 the form shown in Figs. 2, 3, 4 and 5 have their peripheries or cutting edges interrupted or recessed at a single point as indicated at 46, said cutting edges in other words being non-continuous. The interruptions or 30 recesses 46 are preferably formed by removing or omitting pieces of substantially triangular shape from the knives in the manufacture thereof, so that said recesses 46 in consequence have a substantial form as 35 shown in Figs. 2 and 4.

In practice the knives 44 and 45 are secured in any suitable manner, as by screws 47, upon the opposed ends of the drum sections 18 and 19 so as to be located in co- 40 operating pairs in spaced, parallel relation to each other as shown in Figs. 2, 3 and 5. It will be understood that the knives 44 and 45 are positioned so that the recesses 46 thereof will be in registry with each other 45 and further that the diameters of said knives are somewhat greater than the diameter of the drum sections 18 and 19; when operatively combined with the machine the knives 44 and 45 thus form what may be 50 termed cutting flanges which extend beyond the surface of the drum excepting at the recesses 46. The cutting members or knives further include transverse cutting projections 48 which extend transversely between 55 each pair of knives at the points where the bases *a* of the recesses join the cutting peripheries of the knives as shown in Figs. 4 and 5. These transverse cutting projections 48 preferably comprise integral portions 60 of the knives bent at substantially right angles thereto, it being understood that the projection 48 is formed on one of the blades 44 or 45, the other blade of the pair being minus said projection. In the 65 illustrated example the cutting members or

knives in each pair are adjusted with respect to each other and in accordance with the width of the stems to be stripped by shifting the drum sections 18 and 19 on the shaft 16 and are secured in their adjusted 70 positions through the medium of the set screws 21. The cutting or stripping mechanism in the form being described further includes cutting rollers 49 and 50 which are arranged to travel upon and coöperate re- 75 spectively with the cutting edges of the knives 44 and 45 to strip the leaf as will be more fully brought out hereinafter. To provide for a proper coöperation between the knives and the rollers regardless 80 of variations in the cutting edges of said knives or inequalities therein, the rollers 49 and 50 are independently mounted so as to be capable of vibration relatively to each other and of independently adjusting themselves to the cutting members 44 and 45. In the illustrated example the means whereby this is accomplished comprises arms 51 upon which rollers 49 and 50 are respectively mounted, each arm 51 being secured 85 to or preferably forming an integral part of a sleeve 52 rotatably mounted upon a rod 53 mounted upon the frame 15. These sleeves 52 are capable of an independent rocking movement upon the rod 53 and at 90 their outer ends carry levers 54 each of which is controlled by a spring 55 having an end secured to the free end of a lever and its other end fastened to a suitable lug 56 upon the frame 15; these springs 55 each 100 exert a tension upon the levers 54 tending to maintain the rollers 49 and 50 in proper contact with the cutting edges of the knives 44 and 45. In order to arrest the swinging movement of the arms 51 and to prevent the 105 rollers 49 and 50 from contacting with the surface of the booking drum when said rollers are opposite the interrupted or recessed portions of the knives, stops 57 are provided on the frame 15 at proper points 110 to engage the levers 54 and arrest the swinging movement thereof under the influence of the springs 55. To insure the proper ejection of the stems from the machine I provide a resilient member 58 located between the knives 44 and 45. This member 58 has its one end secured for instance to one of said knives by means of a screw 59 and preferably follows the peripheries of 115 said knives in approximately flush relation thereto, the free end of said member preferably lying in close proximity to the recesses 46 as shown in Fig. 4. The machine shown in the illustrated example further includes an idler roller 25 journaled on the 120 frame 15 in coöoperative relation with the roller 25 and together therewith comprising feeding means whereby the tobacco leaf is fed into the machine.

As previously stated, the preferred ar- 130

arrangement includes means whereby the machine is automatically stopped at predetermined intervals to bring the stripping mechanism and booking drum into the proper 5 and desired positions for the proper introduction of successive leaves of tobacco; with the form of cutting members 44 and 45 shown in Figs. 1, 2, 4 and 5 this automatic stoppage would occur at the end of each 10 complete revolution of said cutting members and of the booking drum. As shown in the illustrated example, said means comprises an arm 60 secured upon the transverse shaft 16 so as to project radially 15 therefrom and carrying a rigid lug or pin 61 at its free end. In order to bring about the desired results this arm 60 and its lug or pin 61 must bear a certain relation to the recesses 46 of the knives or cutters 44 and 20 45; said arm 60 is thus preferably adjustably mounted upon the shaft 16 and for this purpose may be provided with a split hub and lugs 62 arranged to exert a clamping action on the shaft 16 through the medium 25 of a bolt or the like 63. The automatic arrangement being described further includes a lever 64 pivoted at 65 upon the frame 15 and adapted to swing vertically between stationary stops 66 and 67; the lever 64 is 30 pivotally connected at 68 with one end of a connecting rod 69, the other end of which is pivotally connected at 70 with one arm of a bell crank lever 71. The latter is pivoted upon a bracket 72 on the frame 15 and 35 has its other arm projecting upwardly into the recess of a hook or the like 73 operatively combined with the lever 37. As shown in Fig. 1 the lever 64 is formed with a slideway 74 in which a plunger 75 is 40 slidably mounted, said plunger 75 normally projecting outwardly beyond said lever 64 into the path of the pin or lug 61 of the arm 60 as the latter rotates with the drum in a manner to be more fully set forth hereinafter. The inner end of the plunger 75 carries a pin 76 which extends into a slot 77 45 formed at one end of a lever 78 pivoted at 79 upon the frame 15, the opposite end of said lever 78 being connected with one end 50 of a spring 80 which has its other end fastened to an ear 81 located on the frame 15. As will be apparent, the spring 80, through the medium of the lever 78, serves to maintain the plunger 75 in and return it to its 55 normal outwardly projecting position. The pivot 79 is in the nature of a pin fixed to the lever 78 and projects through its bearing in the frame 15 where it carries a fixed arm 82 which is operatively connected by 60 means of a connecting link 83 with a treadle 84 pivoted at the bottom portion of the frame 15.

In practice the parts are so adjusted that, in the position of rest of the machine, the

forward ends *b* of the recesses 46 of the 65 knives 44 and 45 are located in substantial registry with the feed rollers 25 and 25^a as shown in Figs. 1 and 2, it being understood that said knives and the drum travel in the direction indicated by the arrows in Figs. 1 70 and 2. At the same time the arm 60 is so positioned on the shaft 16 that its free end with the pin or lug 61 is at the required distance from the ends *b* in a circumferential direction to bring the machine to a stop at 75 the proper point each time for the insertion of successive leaves of tobacco.

In operation, assuming the machine to have been properly started, the tip end *c* of the tobacco leaf *d* is introduced between 80 the rollers 25 and 25^a with the stem of said leaf in registry with the space between the two knives 44 and 45, it being understood that the rollers referred to are properly located to make this possible. As the feed 85 rollers 25 and 25^a are actuated the leaf will be carried along, the belts 22 assisting in the feed thereof; as this happens the portions of the leaf on opposite sides of the stem will lie upon the drum sections 90 18 and 19 and will be held thereon by said belts 22, the tip end *c* of said leaf being located at or in close proximity to the point *b* of the knives 44 and 45. Because of the recesses 46 of said knives the leaf as it is fed 95 into the machine will remain uncut or unstripped for a distance from its end and will consequently retain a portion of its stem approximately equal in length to the distance between the point *b* of the knives and the transverse cutting projection 48. As soon as the latter arrives beneath the rollers 49 and 50 the leaf will be passed between 100 said rollers and the cutting projection 48 and owing to the coöperating action thereof 105 will receive a cut *e* extending transversely of and somewhat beyond the stem on either side as indicated in Fig. 10. From this point the cutting edges or peripheries of the knives 44 and 45 act in conjunction with 110 the rollers 49 and 50 and cut the remainder or butt end portion of the stem from the leaf, so as to strip the latter as indicated at *f* in Fig. 10. It will be understood that the knives 44 and 45 cut the leaf along opposite 115 sides and as close to the butt end portion of the stem as is convenient, the knives being adjusted relatively to each other to produce this result as nearly as possible in all leaves of a given bundle or supply. That portion 120 of the stem which is cut out or stripped caused a depression of the resilient member 58 thus placing same under a tension which causes said stem to be ejected from the machine at the proper time. The leaf after 125 being partly stripped as described, is booked, in the illustrated machine, upon the drum sections 18 and 19 and is held thereon

by the belts 22 with the unstripped portion bridging the space between said drum sections at the recesses 46.

As the machine is operated in the manner set forth the arm 60 will be carried along with the result that the pin or lug 61 thereof will finally engage the plunger 75 from below and thus exert a lifting action thereon. This causes the lever 64 to be swung on its pivot 65 whereby the connecting rod 69 is raised and swings the bell crank lever 71 on its pivot; this brings about an actuation of the lever 37 through the medium of the hook 73 which causes the clutch elements 36 and the pulley 35 to be disengaged and the machine thus brought to a stop. When it is desired to again start the mechanism the treadle 84 is depressed thus exerting a pull upon the link 83 and actuating the arm 82 and lever 78 whereby the plunger 75 is withdrawn from engagement with the pin or lug 61 of the arm 60; as soon as this happens the lever 64 drops back and through the medium of its connected and coöperating parts throws the clutch elements 36 and pulley 35 into operative engagement with each other whereby the machine is again started. The tip end of a new leaf may now be inserted between the rollers 25 and 25^a and the operation repeated, this being continued until the desired number of leaves have been stripped or books of the desired dimensions have been produced. It will be understood, if at any time or for any reason it becomes necessary to stop the mechanism at an intermediate point that the treadle 40 is depressed. This actuates the connecting link 39 and operates the lever 37 to disengage the clutch elements 36 and pulley 35.

In some cases the drum may be designed to hold a plurality of bookings at intervals upon its periphery or the smallness of the leaf being stripped may make this desirable. To provide for this the knives 44^a and 45^a, instead of having their cutting peripheries interrupted or recessed at a single point as are the knives 44 and 45, are provided with two or more recesses 46^a and 46^b as shown in Fig. 6. With this form of cutting members or knives the transverse cutting members similar to the members 48, one for the recesses 46^a and another for the recesses 46^b, may both be carried by or formed on one of the knives in which case the other knife would be minus such projections or one projection 48^a may be carried by or formed on each knife as will be readily apparent. In this case it is also necessary or at least desirable to stop the machine at intervals corresponding to the number of recesses formed in the cutting members; in the form illustrated in Fig. 7 this would mean a stoppage twice in each complete revolution of said knives or of the booking drum. In

order to provide the desired result automatically a double arm 60^a is substituted for the single arm and is adjustably secured upon the shaft 16 by means of a split hub and lugs 62^a and a bolt 63^a; this double arm is provided at its opposite ends with pins or lugs 61^a each of which is adapted to throw out the clutch mechanism in the same way as the single arm 60. Otherwise the construction and operation of the form of my improvements at present being described may be the same as the form first referred to.

It may further be desirable to substitute a single roller 50^a for the rollers 49 and 50, the single roller 50^a being of sufficient width to properly coöperate with the cutting edges of both knives 44 and 45 or 44^a and 45^a as the case may be. In order that such single roller 50^a may adjust itself to inequalities in each cutting periphery or to differences between the cutting peripheries of the knives, it is of advantage to mount said roller so that, in addition to being capable of moving toward and away from the knives, it will be capable of rocking transversely thereto. This may be accomplished in any suitable manner as by mounting the roller 50^a in a forked member 51^a having a stem 51^b rotatably mounted in a bearing 52^a formed on a sleeve 52^b. The latter may correspond to the sleeves 52 and is suitably journaled on the frame 15, the axes of rotation of the sleeve 52^a and stem 51^b being at substantially right angles to each other as shown in Figs. 8 and 9. The roller 50^a is maintained in contact with the cutting edges of the knives by means of springs 55^a and arms 54^a located at opposite ends of the sleeves 52^b and corresponding to the springs 55 and arms 54 of the form first described; the swinging movement of the roller 50^a toward the drum is also preferably arrested by means of stops 57^a coöperating with the arms 54^a and corresponding to the stops 57.

It will be seen, in all the forms of my improvement, that the leaf is only partly stripped in such a manner that the tenderest portion of the stem which is useful for many purposes is permitted to remain as a part thereof and is not wasted; in other words only the toughest, most useless portion of the stem is removed thus reducing waste of material to a minimum. By first cutting the leaves transversely of the stem at an intermediate point and by having this transverse cut extend somewhat beyond the stem in opposite directions a clean cutting of the leaf beyond the transverse cut is assured and tearing is avoided. That portion of the stem which is to be stripped is thus cut cleanly from the leaf without waste and without damage to said leaf. My improvements also make it readily possible to cut closely along that portion of the stem which is to be re-

5 moved so that waste of otherwise useful tobacco leaf is also reduced to a minimum.

10 My improved stripping means and other improvements herein set forth are all simple in construction and efficient and economical in operation. It will, of course, be understood that my improved stripping means may be operatively combined with tobacco machines other than that illustrated and further that said means comprises a mechanism capable of use by itself and without combination with a booking machine.

15 Various changes in the specific forms shown and described may be made within the scope of the claims without departing from the spirit of my invention.

I claim:

20 1. In a stripping machine, a cutting device comprising a cutter whereby the stem of the tobacco leaf is transversely cut at a point intermediate of its ends and cutters whereby a section of said stem extending up to said transverse cut is positively cut from the leaf and means for actuating said cutting device.

25 2. In a stripping machine, a rotatable cutting means whereby the stem of the tobacco leaf is transversely cut at a point intermediate of its ends and longitudinally from said transverse cut whereby a section of said stem extending from said transverse cut to an end of the stem is positively cut from the leaf and mechanism for actuating said means.

30 3. In a stripping machine, a rotatable cutting device comprising combined transverse and spaced parallel cutting members whereby the stem of the tobacco leaf is cut transversely of its length and longitudinally from said transverse cut to positively cut a section of said stem from said leaf and means for actuating said cutting device.

35 4. A stripping mechanism comprising a cutter whereby the stem of the tobacco leaf is cut transversely at a point intermediate of its ends, a pair of co-operating cutting members whereby a double cut is made lengthwise along opposite sides of said stem from said transverse cut to positively cut a section of stem from said leaf and from the remainder of said stem, said cutter extending transversely to said cutting members and being carried thereby, and means whereby said transverse cutter and cutting members are actuated.

45 5. A stripping mechanism comprising cutting means including rotatable devices having non-continuous cutting edges concentric with the axis of rotation whereby a continuous cut is made along the stem of a tobacco leaf and automatically arrested at a predetermined point without interfering with the rotation of said rotatable devices and means for operating said cutting means.

60 6. In a stripping mechanism a pair of co-operating rotatable cutting members arranged in axial registry and spaced from

each other, said cutting members having cutting edges concentric with the common axis of rotation thereof and interrupted at points in registry with each other whereby a continuous double cut is made and arrested at a predetermined point.

65 7. In a stripping mechanism a pair of co-operating circular cutting members arranged in parallel and spaced relation to each other and recessed in registry with each other to form non-continuous cutting edges and a transverse cutting member extending transversely between said circular cutting members.

80 8. In a stripping mechanism a pair of co-operating circular cutting members arranged in parallel and spaced relation to each other and recessed in registry with each other to form non-continuous cutting edges, a transverse cutting member extending transversely between said circular cutting members and rotatable means in rolling engagement with the cutting edges of said cutting members.

85 9. In a stripping mechanism a pair of co-operating circular cutting members arranged in parallel and spaced relation to each other and recessed in registry with each other to form non-continuous cutting edges, a transverse cutting member extending transversely between said circular cutting members and independently mounted rollers in rolling engagement with the cutting edges of said cutting members.

90 10. In a stripping mechanism, a rotatable cutting member having a peripheral cutting edge and a peripheral recess whereby the cutting action of said cutting edge is periodically and automatically interrupted without interfering with the rotation of the cutting member.

100 11. In a stripping mechanism, a rotatable cutting member having a cutting edge concentric with the axis of rotation and a plurality of peripheral recesses whereby the cutting action of said cutting edge is periodically and automatically interrupted at spaced intervals without interfering with the rotation of the cutting member.

110 12. In a stripping mechanism, a rotatable cutting member having a cutting edge concentric with the axis of rotation and a pair of peripheral recesses located at diametrically opposite points whereby the cutting action of said cutting edge is periodically and automatically interrupted without interfering with the rotation of the cutting member.

115 13. In a tobacco stripping and booking machine, a booking drum comprising two sections axially spaced from each other, a pair of circular cutting members secured to the opposed ends of said drum sections and having non-continuous cutting edges, rotatable means in rolling engagement with said

- cutting edges, means for actuating said machine and adjustable means whereby said actuating means is automatically disconnected to stop the machine at predetermined intervals.
14. In a tobacco stripping and booking machine, a booking drum comprising two sections axially spaced from each other, a pair of circular cutting members secured to the opposed ends of said drum sections and having non-continuous cutting edges, rotatable means in rolling engagement with said cutting edges, means for actuating said machine and an adjustable arm operatively connected with said drum sections and cutting members whereby said actuating means is automatically disconnected to stop the machine at predetermined intervals.
15. In a tobacco stripping and booking machine, a booking drum comprising two sections axially spaced from each other, a pair of circular cutting members secured to the opposed ends of said drum sections and having non-continuous cutting edges, a stem ejecting member located between said cutting members, and adjustable means whereby said actuating means is automatically disconnected to stop the machine at predetermined intervals.
16. In a tobacco stripping and booking machine, a booking drum comprising two sections axially spaced from each other, a pair of circular cutting members secured to the opposed ends of said drum sections and having registering recesses at diametrically opposite points whereby the cutting edges of said members are interrupted at diametrically opposite points, resilient stem ejecting members located between said cutting members in co-operative relation to said recesses, 40 rotatable means in rolling engagement with said cutting edges, means for actuating said machine and a double arm adjustably connected with said drum sections and cutting members whereby said actuating means is 45 automatically disconnected to stop the machine twice in each complete revolution of said drum sections and cutting members.
17. In a tobacco stripping and booking machine, a frame, booking means journaled 50 on said frame, a pair of circular cutting members carried by said booking means in spaced relation to each other and having registering recesses whereby the cutting edges of said members are interrupted, a 55 rod carried by said frame, sleeves independently mounted on said rod, arms located at the opposed inner ends of said sleeves, a roller carried by each arm and arranged to independently engage the cutting edges 60 of said cutting members, levers at the outer ends of said sleeves, springs connected with said levers whereby said rollers are maintained in contact with said cutting edges and stationary stops co-operating with said 65 levers to maintain said rollers out of contact with the booking means when opposite the recesses of said cutting members.

In testimony whereof I have hereunto set my hand.

GRAHAM H. JACKSON.
